DOUBLE IGNITION FOR INTERNAL COMBUSTION ENGINES

Wilhelm Walther, Stuttgart, and Alfred Grob,
Cannstatt, Germany, assignors to Robert Bosch
Aktiengesellschaft, Stuttgart, GermanyApplication January 5, 1932, Serial No. 584,860
In Germany January 9, 1931

3 Claims. (Cl. 123—148)

The present invention relates to a double ignition for internal combustion engines, in which both ignition circuits are controlled by a double interrupter having a common cam. In many cases a double ignition is provided only for one engine in order to have a reserve ignition device in case of need. Hitherto the interrupter of the auxiliary or reserve ignition device which was not in operation constantly ran idle and therefore became worn as much as the working interrupter, so that it might happen that the reserve ignition device became incapable of operation by the wearing out of its interrupter and failed to act when it was needed. It is already known in a single ignition device to employ a double interrupter in which the rocking contact lever can be brought by a device alternately mechanically into and out of contact with the cam. The two interrupters of this double interrupter are arranged in parallel, so that on raising the one rocking contact lever the other is automatically brought into operation.

According to the present invention, such a double interrupter is employed for a double ignition in which each interrupter belongs to a separate ignition circuit. By this means the above-mentioned drawback is avoided, and furthermore the advantage attained that by the double interrupter the ignition apparatus which is not used remains without current.

An example of construction of the invention is illustrated in the accompanying drawing.

In the drawing, A denotes a double interrupter having the two interrupters B and C, D a magneto electric ignition apparatus, and E an ignition coil. The double interrupter has two stationary contacts 1, 2, which are fastened on the base-plate 3 of the interrupter. The corresponding movable contacts 4, 5 are mounted on springy bands 6, 7 which are firmly connected to blocks 8 and 9 of insulating material. The blocks can rock about pins 10 and 11, and are turned by springs 12, 13 towards the stationary contacts. The springs are secured in an insulated manner to lugs 14, 15 on the base-plate. The screws 16, 17 serve for securing the springs and in addition also for the current supply. The blocks 8, 9 can be adjusted by a lever arrangement 18 which may be actuated by an eccentric 19, in such a manner that when the projection 20 of the one interrupter touches the cam 21, the projection 22 of the other interrupter is lifted from the cam so that it is placed out of action. To the terminal 16 of the interrupter B is connected the end of the primary winding 25 of the magneto

ignition apparatus D connected with the secondary coil 24. The other end of the primary coil is connected to earth. The free end of the secondary coil is connected with a distributor 26 through a change-over switch 27. To the terminal 17 of the interrupter C is connected one end of the primary winding 28 of the ignition coil C. The other end is connected with the secondary winding 29 and with the battery 30. The free end of the secondary winding 29 is also connected with the switch 27.

In the drawing the magneto D is in operation. The rods 18 of the double interrupter are so disposed that the projection 20 touches the cam 21 and therefore the interrupter B is in operation. The switch 27 connects the secondary coil 24 of the magneto D with the distributor 26. If the magneto stops for any reason, the ignition coil E can be brought into operation in the simplest manner as a substitute ignition device by turning the rocking lever 9 of the interrupter C, by means of the eccentric 19 and the rods 18, so far towards the stationary contact 2 until the projection 22 comes into contact with the cam 21, and then reversing the switch 27 so that it connects the secondary coil 29 of the ignition coil E with the distributor 26.

We declare that what we claim is:

1. An ignition arrangement for internal combustion engines comprising two separate ignition systems including an interrupter having two contact breakers and a common actuating cam, one of said contact breakers connected with the primary coil of one of said ignition systems, the other contact breaker connected with the primary coil of the other ignition system, and means to alternatively bring the levers of said contact breakers into engagement with said cam.

2. An ignition arrangement as claimed in claim 1, having a common distributor, and a switch for alternately connecting said distributor with the secondary coils of said ignition systems.

3. An ignition arrangement for internal combustion engines including a magneto and an ignition coil, an interrupter having two contact breakers and a common actuating cam, one of said contact breakers being connected with the primary winding of said magneto, the other contact breaker being connected with the primary coil of said ignition coil, and means to alternatively bring the levers of said contact breakers into engagement with said cam.

WILHELM WALTER.
ALFRED GROB.
